(57) **CLAIM**

The ornamental design for a tool, as shown and described.

DESCRIPTION

FIG. 1 is a side elevational view of the tool shown opened, and showing our design;

FIG. 2 is a perspective view from one side thereof showing the tool partially opened;

FIG. 3 is a perspective from another side thereof showing the tool partially opened;

FIGS. 4–8 are perspective views thereof; each element of the tool is shown separately in a similar position of use;

FIGS. 9–13 are perspective views showing the tool in partially opened positions; and,

FIGS. 14 and 15 are top and bottom perspective views, respectively, showing the tool in a closed position.
